COMBINED AUTOMOBILE FENDER MOLDING AND ORNAMENT

Carl E. Sykes, Norfolk, Va.

Application May 24, 1949, Serial No. 2,835

Term of patent 14 years

(Cl. D72—1)

To all whom it may concern:

Be it known that I, Carl E. Sykes, a citizen of the United States, residing at Norfolk, county of Norfolk, and State of Virginia, have invented a new, original, and ornamental Design for Combined Automobile Fender Molding and Ornament, of which the following is a specification, reference being had to the accompanying drawing, forming part thereof, and wherein:

Figure 1 is a perspective view of a combined automobile fender molding and ornament, showing my new design;

Figure 2 is a top plan view of the same;

Figure 3 is a side elevational view;

Figure 4 is a front elevational view showing the lens and its associated parts;

Figure 5 is a vertical sectional view taken on the line 5—5 of Figure 3, looking in the direction of the arrows;

Figure 6 is a vertical sectional view taken on the line 6—6 of Figure 3; and

Figure 7 is a vertical sectional view taken on the line 7—7 of Figure 3.

I claim:

The ornamental design for a combined automobile fender molding and ornament, substantially as shown.

CARL E. SYKES.
